UNITED STATES PATENT OFFICE.

OMER C. TROUT AND WILLIAM T. MARTIN, OF OMAHA, NEBRASKA.

SMOKE-PRODUCING DEVICE.

Application filed January 30, 1922. Serial No. 532,834.

To all whom it may concern:

Be it known that we, OMER C. TROUT and WILLIAM T. MARTIN, citizens of the United States, residing at Omaha, in the county of Douglas and State of Nebraska, have invented certain new and useful Improvements in Smoke-Producing Devices, of which the following is a specification.

The present invention relates to a smoke producing device of that character which may be used in smoke houses for the treatment of packing house products, such as meats and the like.

An object of the present invention is to provide a device of this character which is adapted to produce a relatively large volume of smoke compared to the amount of fuel consumed; and to provide a device or furnace of this character which is automatic in action and which is capable of burning saw dust and the like.

Another object of the invention is to provide a device by the use of which time and labor are saved in the smoking of meats, material is conserved, the necessity of using wood is eliminated, a device which when used will affect a relatively smaller percentage of shrinkage of the meats than prior used devices, and which is sanitary, increases the appearance and flavor of the products and reduces the time and space required in smoking or treatment of the meats.

Briefly stated, the present invention aims at the provision of a smoke producing device which carries a quantity of fuel and automatically feeds it into position for consumption, and which employs pneumatic means for agitating the fuel in such manner as to prolong the consumption thereof and effect the generation of a relatively large volume of smoke.

With the foregoing and other objects in view, the invention will be more fully described hereinafter, and will be more particularly pointed out in the claims appended hereto.

In the drawing, wherein like symbols refer to like or corresponding parts throughout the several views.

Fig. 1 is a perspective view of a smoke producing device constructed according to the present invention, parts being broken away to expose the interior portions of the device, and

Fig. 2 is a fragmentary enlarged section taken vertically through one side portion of

the device, showing the adjacent fuel magazine and the surrounding parts.

Referring to the drawing 10 designates a casing or enclosure which constitutes the body portion of the furnace, and which may be of any suitable dimensions, construction and material. In the present instance the receptacle 10 is shown as being open at its top, although the same may be closed in any suitable manner if desired, but such closure would necessitate outlets or vents for the exit of smoke into the store-room or enclosure within which the smoke producing device may be positioned.

The casing 10 is provided in its lower end with a horizontal grate 11 of any suitable construction but which in the present instance comprises a plate having apertures 12 therethrough for passage of air upwardly through the grate and for the settling of ashes into the ash pit or compartment in the bottom of the casing 10. The grate 11 may be supported by cleats 13 from the walls of the casing 10, and the casing 10 is provided with a door 14 in a side wall through which the ashes may be removed from the ash pit.

The casing 10 is provided with storage means for fuel, and in the present instance such means embodies one or more hoppers 15 into which saw dust or the like is adapted to be placed for feeding downwardly to the grate 11. In the present instance two such hoppers 15 are shown while any desired number may be used, and the hoppers extend lengthwise in the opposite sides of the casing 10 and taper downwardly, and each hopper has a pair of shutters or valves 16 at its lower end for controlling the passage of the fuel downwardly from the hopper. The shutters or valves 16 are in the form of leaves which extend throughout the length of the hopper 15 and which are hinged thereto at the lower edges of the sides of the hopper. The shutters or valves 16 are each mounted upon a rod 17 mounted for rotation into the opposite sides of the hopper, and the rods 17 have their ends turned at substantially right angles to form cranks 18 by means of which the rods may be turned and the valves 16 adjusted.

These cranks 18 are preferably located at one end of the casing 10 and the pair of cranks 18 of each hopper are extended in opposite directions and are connected together by a link 19 which causes the rods 17

to turn in opposite directions when either one of the rods is operated. Each pair of rods 17 is similarly connected, and an operating bar 20 is pivotally connected at spaced 5 apart points to a corresponding crank 18 of each pair of rods so that operation of the bar 20 in one direction causes all of the valves 16 to open, and operation of the rod 20 in an opposite direction causes all of the 10 valves to close.

As shown in Fig. 2 each hopper 15 may be supported upon uprights or standards 21 which are secured at their upper ends to the sides of the hopper 15 and which rest at 15 their lower ends upon the grate 11 to support the lower end of the hopper 15 in spaced relation above the grate 11. This arrangement of the hopper above the grate provides ample room for operation of the 20 valves 16 and also provides a suitable space for the fuel to fall and to move when agitated, as will be subsequently brought out.

The casing 10 is provided at each side of the hopper 15 with an air pipe 22 having 25 outlet nozzles or the perforations 23 directed axially downwardly at substantially 45 degrees toward the grate 11 and toward the hopper 15. The blasts of air issuing from the nozzles or openings 23 are adapted to 30 blow toward the grate 11 and beneath the hopper and to agitate the fuel after the fuel has fallen upon the grate 11. Where the pipe 22 is located between a pair of hoppers 15, the pipe may have the nozzles 23 formed 35 in opposite sides thereof so as to provide jets of air, which issue beneath the hoppers and in such directions as to maintain the fuel in a constant state of agitation.

Each fuel pipe 22 projects through one 40 end of the casing 10 and each has an individual valve 24. The pipes 22 are connected to a supply manifold 25 which is connected to a supply pipe 26 in which is placed a controlling valve 27 for supplying air under the 45 desired pressure to the manifold 25 and the pipes 22.

When the device is in use it is placed in a room or compartment in which are suspended the products to be smoked, such as hams, 50 bacon and the like. The hoppers 15 are now filled with saw dust which produces the most appropriate smoke for treating the particular kind of meat. Birch or other saw dust will produce smoke for imparting 55 different flavors and colors to the various meats, in accordance with the age, quality and kind of meat which is smoked. The saw dust may be saturated with water or chemicals to produce desired results.

60 The saw dust is adapted to fall by gravity from the hoppers 15 and the falling of the saw dust or other fuel used is regulated by manipulating the bar 20 for opening or closing the valves 16 to the desired extent. 65 The fuel is kindled on the grate 11, and as

the fuel drops from the hoppers it is ignited by contact with the grate and with the burning fuel thereon. The pairs of valves 16 of the hoppers provide throats for insuring the even distribution of saw dust over the surface area of the grate, and this even distribution is augmented by the air blasts from the pipes 22 which agitate the saw dust as soon as it drops upon the grate. The grate 11, being hot, partially ignites the particles 75 of saw dust as soon as they strike the grate, and before the particles are completely consumed, the air blasts lift the particles from the grate and violently agitate the same, permitting them to fall from time to time 80 back upon the grate where they can become ignited. The particles of fuel are thus maintained in a partially ignited state so as to produce a relatively large volume of smoke by the delayed consumption of the fuel and 85 the result is that there is considerable economy in the use of the fuel and but little heat is generated. It is this lack of heat which offsets the shrinkage of the products being treated, and at the same time the 90 products are thoroughly smoked in a relatively short time by the relatively large volume of smoke produced. Where the opposed pipes 22 are used at opposite sides of the 95 hopper, counter air currents are produced which meet beneath the hoppers and which increase the agitation of the fuel so as to thoroughly mix it and keep it in practically constant motion. The fuel is thus slowly 100 but completely consumed with the production of but little heat and a relatively large volume of smoke.

The air pressure in the pipes 22 may be individually regulated by the valves 24, and also by the main valve 27 by means of which 105 the main air supply may be regulated for proportionate distribution to the pipes 22.

We do not wish to be restricted to the size, form, and proportions of the various parts, and obviously changes could be made 110 in the construction herein described without departing from the spirit of the invention, it being only necessary that such changes fall within the scope of the appended claims.

115 What is claimed is:

1. In a smoke producing device, an enclosure, a grate arranged in the lower end of the enclosure, a hopper arranged in the enclosure above the grate and having an outlet opening of less area than the grate and adapted to deliver fuel thereto, and fluid jet means located at opposite sides of the hopper and operable against the grate beneath the outlet opening. 120

2. In a smoke producing device, an enclosure having a grate therein, a fuel hopper arranged in spaced relation over the grate and having a lower outlet end of less area than the grate and through which fuel 125

may dropped upon the grate, and air blast devices arranged on opposite sides of the hopper for directing jets of air beneath the hopper and against the fuel as the latter 5 drops upon the grate.

3. In a smoke producing device, an enclosure having a grate therein, a fuel hopper arranged in the upper part of the enclosure and spaced above the grate, shutters 10 at the lower end of the hopper for regulating the dropping of fuel on the grate, and air blast devices arranged at opposite sides of the hopper and having outlet means di-

rected downwardly beneath the hopper whereby to project jets of air in converging 15 relation upon the grate, and beneath the hopper to agitate fuel as the latter strikes the grate.

In testimony whereof, we have affixed our signatures in presence of two witnesses.

OMER C. TROUT.
WILLIAM T. MARTIN.
